(57) CLAIM

I claim the ornamental design for a table, as shown and described.

DESCRIPTION

FIG. 1 is a front, top perspective view of a table, showing a first embodiment of my new design;

FIG. 2 is a rear, top perspective view thereof;

FIG. 3 is a first side, top perspective view thereof;

FIG. 4 is a second side, top perspective view thereof;

FIG. 5 is a front, bottom perspective view thereof;

FIG. 6 is a rear, bottom perspective view thereof;

FIG. 7 is a front elevation view thereof;

FIG. 8 is a rear side elevation view thereof;

FIG. 9 is a first side elevation view thereof;

FIG. 10 is a second side elevation view thereof;

FIG. 11 is a top plan view thereof;

FIG. 12 is a bottom plan view thereof;

FIG. 13 is a front, top perspective view of a table, showing a second embodiment of my new design;

FIG. 14 is a rear, top perspective view thereof;

FIG. 15 is a first side, top perspective view thereof;

FIG. 16 is a second side, top perspective view thereof;

FIG. 17 is a front, bottom perspective view thereof;

FIG. 18 is a rear, bottom perspective view thereof;

FIG. 19 is a front elevation view thereof;

FIG. 20 is a rear side elevation view thereof;

FIG. 21 is a first side elevation view thereof;

FIG. 22 is a second side elevation view thereof;

FIG. 23 is a top plan view thereof; and,

FIG. 24 is a bottom plan view thereof.

The broken lines depict portions of the table that form no part of the claimed design.

1 Claim, 13 Drawing Sheets
